INVENTOR

Paul Heine,

BY

John J. Thompson
ATTORNEY

UNITED STATES PATENT OFFICE.

PAUL HEINE, OF LANCASTER, PENNSYLVANIA.

BUNG.

974,378.

Specification of Letters Patent.

Patented Nov. 1, 1910.

Application filed November 6, 1909. Serial No. 526,504.

To all whom it may concern:

Be it known that I, PAUL HEINE, a citizen of the United States, residing at Lancaster, in the county of Lancaster and State 5 of Pennsylvania, have invented certain new and useful Improvements in Bungs, of which the following is a specification, reference being had therein to the accompanying drawing.

10 My invention relates to bungs for beer-kegs and other similar vessels, and more particularly to that class which are driven into a bushing which has been secured in the keg in such a way that to tap the keg, the 15 central portion of the bung is driven inward through the bung to provide a place for the spigot, and when it is desired to refill the keg, the shell of the bung is removed and a new bung inserted.

20 My novel form of bung is so constructed from a single piece of wood or other suitable material that the central core or plug is nearly separated therefrom by means of an incision which is so made that the plug is 25 tapered in form to prevent its being blown outward by the action of gases, etc., but may easily be driven inwardly, severing the integral portion or ring.

To close the incision and make the bung 30 tight, the bung is first made with straight parallel sides, the incision then made at the proper angle and the bung then pressed in a die which forces in the sides to close the 35 incision and give the outer sides of the bung the proper taper to conform to the tapered hole of the bushing.

With these and other objects in view my invention consists in certain construction and combination of parts as will hereinafter be 40 fully described and claimed in the annexed specification and fully illustrated in the accompanying drawings, which form a part of this application, and in which like figures of

reference refer to corresponding parts in all of the views; but it is fully understood that 45 while I have here described my invention as here shown, that I do not confine myself to the exact design as shown, as slight changes may be made in the construction and arrangement of the several parts without de- 50 parting from the spirit of the invention.

In the drawings:—Figure 1, is a vertical sectional view of a bung, showing the straight sides and the incisions having been made. Fig. 2, is a view of the same, after 55 having been pressed, showing the incision closed and the sides of the bung tapered, ready for use. Fig. 3, is a sectional view of the same, placed within the bushing. Fig. 4, is a view of the same, after the plug has 60 been driven out. Fig. 5, is a top plan view of the bung. Fig. 6, is a bottom plan view of the bung.

Referring to the drawings:—the bung is shown with the side walls 1, the plug 2, 65 which is integral therewith at the ring 3, and the incision 4, which is cut upon a taper as described.

Having thus described my invention what I claim as new and desire to secure by Letters Patent is:—

A bung made of a single piece of material and provided with a separable plug or core having tapered sides and integral at its upper end with said bung; said bung having 75 been given a conical shape under pressure so as to close the incision and make it practically solid, but not destroying the taper of said plug.

In testimony whereof I affix my signature 80 in presence of two witnesses.

PAUL HEINE.
